UNITED STATES PATENT OFFICE.

WILLIAM H. CLARK, OF ROCHESTER, NEW YORK, ASSIGNOR, BY MESNE ASSIGNMENTS, TO THE NATIONAL CASH REGISTER COMPANY, OF JERSEY CITY, NEW JERSEY, A CORPORATION OF NEW JERSEY.

COMPUTER AND PRINTER.

SPECIFICATION forming part of Letters Patent No. 773,057, dated October 25, 1904.

Application filed December 9, 1898. Serial No. 698,798. (No model.)

To all whom it may concern:

Be it known that I, WILLIAM H. CLARK, a citizen of the United States, and a resident of Rochester, in the county of Monroe and State 5 of New York, have invented certain new and useful Improvements in Computers and Printers, of which the following is a specification.

This machine is a complete computer and printing device and is an improvement upon 10 devices heretofore produced by me; but many parts and arrangements in the machine constitute more than mere improvements upon said prior devices and are, in fact, new and independent inventions.

15 The object of the invention is to produce an improved and efficient total-adding computing-machine with a printing device capable of printing the individual amounts registered by the machine and of printing the sum 20 total of the amounts registered.

The invention consists in the mechanisms and combinations herein described and claimed.

In the drawings, Figure 1 is a top plan view 25 of a machine embodying the improvements set forth herein. Fig. 2 is a front elevation, parts of the casing and parts of the interior mechanism being removed in order to exhibit construction, the line 2 2 of Figs. 6, 7, and 8 showing the line on which the views

30 of the right and left hand portions of this figure are taken. Fig. 3 is a top plan of the feeding mechanism for the printing-ribbon. Fig. 4 is a section on the line 4 4 of Fig. 3 looking in the direction of the arrow in the latter figure. Fig. 5 is a rear view of the machine, the rear plate of the case being removed and some of the interior parts being removed to exhibit construction. Fig. 6 is an elevation of one end of the machine, the 35 end casing-plate being removed. Fig. 7 is an elevation of the other end of the machine, the end casing-plate being removed. Fig. 8 is section on the line 8 8 of Figs. 2 and 5 looking in the direction of the arrow in those figures.

40 Fig. 9 is a section on the line 9 9 of Figs. 2 and 5 looking in the direction of the arrow in those figures. Fig. 10 is a detail view of part of the platen-setting mechanism. Fig. 11 is

a side elevation of one of the computing-wheels and certain of its appurtenances. Fig. 12 is 50 a section on the line 12 12 of Fig. 11. Fig. 13 is a top plan of the setting-bars and certain related mechanisms, parts being removed on the line 13 13 of Fig. 8 to exhibit construction. Fig. 14 is a partial rear elevation of 55 the machine with certain parts removed and certain parts shown in section on the line 14 14 of Fig. 8. Fig. 15 represents an end elevation of the cam-plate α , and Fig. 16 represents a similar view of the cam-plate α' . 60

The machine contains a key mechanism consisting of the finger-pieces connected to and operating longitudinally-movable bars, which by displacement from their normal positions of rest are adapted to be moved in 65 paths whereby contact can be made with movable setting parts of a registering mechanism. The movable bars are moved in a particular path upon each operation of the machine and when in the ordinary position of rest do not 70 come in contact with the setting parts above mentioned, but, as explained, when displaced do make such contact.

In the form of device shown the longitudinally-movable setting-bars A are pulled in 75 one direction by springs a , each bar being independent of the others in its movements. The bars A are held in the displaced or setting positions by means of dogs A', which snap into notches a'' upon the upper edges of 80 said bars. The dogs A' are normally held down either by gravity or by springs a' . It is convenient, as in the construction shown in the drawings, that a single dog should be adapted to engage all the bars relating to a 85 single denomination, although separate dogs for each bar would be an equivalent form. The set of dogs for all the denominations of a machine constructed according to my invention are strung upon a bar a''' , and there 90 is a small amount of loose movement as between the bar and each dog, so that the dogs may engage in the notches of the setting-bars without affecting the position of the bar upon which they are strung. This loose connection 95 consists in a slot a'''' in the dog and a pin a''''' ,

extending from the bar a^01 into the slot. (See Fig. 13.) Whenever in the operation of the machine it becomes desirable to disengage all the dogs, the bar upon which they are strung 5 is turned by means hereinafter described, raising and disengaging all the dogs from the bars which have been set, and thus permitting all the setting-bars A to return to their normal position impelled by their respective 10 springs a . It will be noted as the further parts of the machine are described that the dogs A' are released for a short time only at the end of the positive stroke of the motor or crank.

15 The front end of each setting-bar is connected to one arm of a bell-crank lever A¹⁰, that is suitably pivoted to the frame of the machine, and the other arm of said lever is connected to the stem of a key or finger-piece A², so that when the finger-piece is depressed the setting-bar A is moved longitudinally until it is caught and held by its dog A', as above described. In the form of device shown there are two notches a^0 in the 20 upper edge of each setting-bar A, in one of which the dog A' normally rests and in the other of which the dog rests after the finger-piece has been depressed and the bar is displaced.

25 The bell-crank levers A¹⁰ are formed with sleeves a^{10} , which are strung on rods a^{100} , running across the machine. (See Fig. 13.) The setting-bars are in each denomination graduated in length, as shown in Fig. 13, so 30 that the finger-pieces A², relating to each denomination, may be set in parallel rows, as shown in Fig. 1.

The inner end of each setting-bar A is turned at right angles to its length, as at a^{00} , Fig. 40 13, or has a lug upon it, the cheapest construction, however, being to make the bar thin in order to produce compactness of construction and to turn the end of the bar at right angles, as above described.

45 In addition to the key mechanism just described the machine has a setting mechanism, a registering mechanism, and an operating mechanism. The free or rear ends of the 50 whole series of setting-bars A of all denominations rest upon a universal plate or stirrup A³, that is caused to rise and fall, by means hereinafter described, in order to make contact with the setting mechanism and to operate it. The time of the movements of the 55 stirrup is at the beginning of the positive stroke of the motor or handle for reasons that will be explained. The stirrup A³ is hung at each end upon a pin a^3 , that forms the connecting-pivot to one arm of a bell-crank 60 lever a^{30} , the fulcrum a^{31} (see Figs. 6 and 7) of said bell-crank lever being a rod passing across the machine and through the end frame X X' of the machine and outside thereof. The other end of this bell-crank lever is provided 65 with a friction-roller a^{32} and is operated as

will be described. There is one of these bell-crank levers at each end of the machine, so that the stirrup rises and falls evenly. The weight of the stirrup is sufficient to return it to place after it has been raised; but a 70 spring may be employed in place of gravity, or to assist it, if desired.

The general system of the registering mechanism of this machine is of the ball variety, such as is well known from my prior United States 75 patents, although it is greatly changed in certain respects, as will clearly appear. The balls in this machine move in circular paths in a groove or way B, formed in the periphery of a ring. In the present embodiment of my 80 invention this ring is the rim of a wheel B', and the wheel moves with the balls to force them around in their paths. After the wheel has moved to the proper degree the balls are held stationary while the wheel makes its 85 further or non-registering movement.

In order to set the machine for operation, I provide a universal bar C, swinging about a center and inside the ring or rim of the wheel B' above mentioned. This bar is common to all the registering mechanisms of the 90 several denominations and has a uniform path of movement corresponding to the stroke of the power device or handle.

Through the center of the machine passes 95 the main shaft D, carrying at one end the crank D⁰ and handle D¹⁰⁰ and also carrying near each end of the main shaft a cam-plate x x'. The two cam-plates are outside the end plates X X', which support various mechanisms of the machine. These two cam-plates are rigidly fastened upon the main shaft, and hence move together as if one, and to them are fastened the ends of the universal bar C above mentioned. Upon one of the cam-plates x', Fig. 7, is placed the ratchet-segment x¹⁰, adapted to engage with a fish-tail dog x¹¹, in order to compel full stroke of the operating device or crank after the handle has 100 been started. Pins x¹² x¹³, carried by the cam-plate, tilt the lever attached to the fish-tail dog when either end of the stroke of the cam-plate is reached, and a spring x¹⁴, having the wedge or tooth x¹⁵ upon it, engages on 105 one side or the other of the wedge-tail of the pawl and holds the pawl in the proper position for permitting the movements desired. Thus full stroke, first in the positive direction and then backward in the negative direction, is compelled with a uniform forward 110 and backward movement of the universal bar C and of the cam-plates x and x'. 115

Around the main shaft D and between the 120 end plates X X' is a sleeve D', that is fastened to the end plates, so as not to be moved either by the rotation of the shaft within it or by the rotation of the parts which surround it. Upon this stationary sleeve D' is strung a 125 series of the wheels B', one for each denomination, each having in its rim or periphery 130

the ball-groove B above mentioned. Each ball-wheel carries a setting mechanism for determining the amplitude of the arc of vibration by which a particular number of units 5 shall be counted by that wheel. This setting device (see Figs. 11 and 12) consists of a frame b, rigidly secured to said ball-wheel and having two brackets b⁰ b⁰⁰, (see Fig. 12), extending substantially at right angles to the plane 10 of the wheel and formed in arcs drawn from the center of this wheel. Through these brackets pass a series of nine pins b¹⁰, supported and guided by the brackets. These pins are set in radii of the circle of the wheel and in 15 the same plane and are impelled outward or away from the center of the wheel by suitable coiled springs b¹¹, surrounding the pins and in each case pressing against a collar or flange b¹² upon the pin and also against one of the 20 brackets. Each pin is also cylindrical and is provided with a conical tooth b¹³, said tooth being made conical or circular in cross-section in order that it may engage in any position with a catch or dog, hereinafter to be described, 25 and also for ease of manufacture. To the frame b is fastened by suitable arms b¹⁴ a dog b¹⁵, which is universal as to each set of nine pins. This dog when the pins are impelled outward by their springs and rest in their re- 30 tracted positions rests against the outer surface of the cone; but when the pin is moved inward toward the center of the wheel the dog engages under the base of the cone and holds the pin in an extended position. Springs of 35 suitable form, such as the flat spring b¹⁶, tend to keep the universal dog pressed inward toward the pins. The dog has an extension or arm b¹⁷ on one end or at any suitable point, whereby it may be released from any of the 40 pins that have been operated, as hereinafter described.

The sets of setting-frames b above described are preferably set in line across the machine and at substantially the lowermost point of 45 each of the ball-wheels and are immediately above the rectangular bent ends a⁰⁰ of the setting-bars A above described. In the normal position of the parts the ends of the pins do not register with the ends of the setting-bars, 50 (see Figs. 8 and 9;) but when any setting-bar is displaced from the normal position by the depression of its finger-piece the end a⁰⁰ of said bar is brought under the end of its pin, and when the stirrup A³ is raised that bar a⁰⁰ 55 will make contact with the end of the pin and will raise it until it is latched in its projected position by the universal dog b¹⁵ above described. No other pin, however, in that denomination will be moved, because the bent 60 ends a⁰⁰ of the setting-bars A are so adjusted as to pass between pins without making contact with them. If now the universal bar C within the ball-wheels is swung through its arc, it 65 will strike the pin b¹⁰, that has been projected into the path of said bar, and on account of

the position of the projected pin b¹⁰ the ball-wheel will be moved through an arc corresponding to the value of the pin, because the bar C always moves through a definite arc. It will be noticed that the pins b¹⁰ are set in 70 a plane parallel to the plane of movement of the ball-wheel and that the universal bar has a constant path of movement, ending against a stop. If "9" is to be counted, a pin is projected into the path of the universal bar by 75 the means above described and is the pin nearest to the normal position of rest of said bar. Thus this "9" pin is the first against which the universal bar can strike, and hence the bar C swings the wheel B' through the maximum 80 stroke or arc of movement of the wheel. The "1" pin is set farthest away from the normal position of rest of the universal bar C and is the last pin with which said bar could come in contact, thus making the distance from the point 85 of contact to the stop the shortest arc of movement of which the wheel is capable. In Fig. 11 the "6" pin is shown projected into the path of movement of the universal bar C.

In order that in operating the machine 90 quickly the stroke of the universal bar against a raised pin may not drive the wheel with greater speed than the bar, I provide a latching device (shown best in Fig. 11) that locks or connects the universal bar to the ball-wheel. 95 Upon the universal bar is a dog c⁰¹, that is operated either by gravity or by a spring to engage with a series of ratchet-teeth b⁰¹ upon the ball-wheel B' or, as shown, upon the pin-frame b. When the bar C strikes a pin, the 100 dog c⁰¹ engages a tooth of the ratchet b⁰¹ in such a position as to lock the bar against the pin and to prevent either forward action of the ball-wheel with reference to the universal bar or a rebound of the universal bar from 105 the pin. In order to operate this dog, a convenient mechanism is shown, in which the dog c⁰¹ has a projecting V-shaped tail c⁰² adapted to engage with the V-shaped tail of a small bell-crank lever c⁰³, also carried by the universal bar C. This bell-crank lever is held by a spring c⁰⁴ in a position adapted to engage with the V-shaped tail of the pawl. The other arm of the bell-crank lever c⁰³ is adapted to 110 engage with a stationary hook-shaped bunter c⁰⁵, which holds said arm of the lever c⁰³ down and swings its V-shaped arm forward and out of the path of movement of the tail c⁰² upon the pawl c⁰¹. If the pawl c⁰¹ is in its lowermost position, its V-shaped tail engages in 115 front of the V-shaped arm or tail of the bell-crank c⁰³, and the spring c⁰⁴, operating upon the bell-crank c⁰³, will therefore latch the pawl c⁰¹ in its lower or engaging position and hold it in this position by the elastic pressure of 120 the spring c⁰⁴, which operates the bell-crank. As soon as the universal bar C begins to move the bell-crank c⁰³ is released from its bunter c⁰⁵, and its spring c⁰⁴ presses the pawl c⁰¹ with 125 an elastic pressure against the ratchet-teeth, 130

thus being adapted to latch the parts as above described. As the universal bar approaches the limit of its positive stroke a stationary bunter c^{os} strikes the tail c^{os} of the pawl, drives it past the tail of the bell-crank lever c^{os} , and thus latches the pawl in a raised position, whereby it cannot engage the ratchet-teeth, and thus a free return stroke of the parts can occur. It will be observed that the universal bar has a uniform stroke, but that the ball-wheels have variable strokes, according to the amount to be computed thereon.

Each ball-wheel B' carries on its lower portion a dog b' , (see Fig. 8,) that projects into the groove B, wherein the balls Y move, and at a suitable point in the upper part of the machine another but stationary dog b^{os} is provided for each ball-groove, the whole series of which dogs b^{os} are hung loosely to the frame 70 of the machine upon a suitable cross-bar b^{os} . A second stationary dog b^{os} is provided for each ball-groove and projects into the same in the lower part of the wheel conveniently in a position opposite to that of the dog b' first 75 above mentioned. The stationary dogs b^{os} are fastened upon a shaft b^{os} , extending across the machine, and are moved positively in and out of the ball-groove B in order to hold the balls stationary during the return movements of 80 the wheel. The shaft b^{os} is rocked upon each movement of the cam-plate ω by a pawl b^{os} . This pawl is normally held in the position shown in Fig. 6 by a spring b^{os} . The cam-plate b^{os} is mounted on the plate ω and is 85 formed at opposite ends with cam-shoulders which engage and rock the pawl b^{os} in opposite directions in a manner well known in the art. If the ball-wheel B' is revolved by the means above described through an arc 90 corresponding, for instance, to six balls, the dog b' upon the ball-wheel holds a number of balls stationary with reference to said wheel, but forces them past the stationary retaining-dog b^{os} at the upper part of said wheel, so that 95 these balls pass onward into that portion of the groove devoted to the registering or computing. This occurs on the forward stroke of the wheel, which takes place in the direction of the arrow in Fig. 11. If now the stationary dogs b^{os} at the lower part of the wheel are brought into engagement with the balls in the groove and the wheel is turned backward, the whole series of balls in the groove remain stationary, while the wheel returns to 100 its normal position.

If a key A², representing "6," is depressed and the corresponding pin b^{os} is raised, the universal bar C passes over the ends of pins representing "7," "8," and "9," strikes against the 105 pin representing "6," swings the ball-wheel B' through six of its nine degrees of movement until the universal bar C strikes against the ends of the slots C' in the end plates X X', through which said bar passes. The wheel 110 B' is thus moved through an arc equal to six

times the diameter of a single ball upon the wheel, and in the series of balls six balls are forced past the retaining-dog b^{os} at the top and fall down in the registering-channel.

It will be noticed that the groove in that 70 portion of the wheel B' at the back of the machine and extending between the retaining-dog b^{os} at the top and the dog b' , carried by the wheel, is always full of balls and that consequently when the wheel moves in its positive 75 direction one or more balls must be pushed past the retaining-dog b^{os} at the top. A suitable vacant space is left in the groove by adjusting the number of balls properly and in filling the same. This space it has been found 80 in practice must be equal to at least twenty ball diameters and is preferably greater than that in order to give a place for registering strictly and a space for retaining the balls before permitting them to drop into the registering portion B¹⁰, Fig. 11, of the groove.

In order to release universal dogs b^{os} of the pin-frames, I provide a bar b^{os} , running across the machine and provided with a series of pins b^{os} , (see Figs. 8 and 12,) one for each dog b^{os} , and adapted in the normal position of rest to stand adjacent to the sides of the extensions or arms b^{os} upon universal dogs. After the return or negative stroke of the machine the bar b^{os} is moved endwise. The pins come 95 against the arms b^{os} of the respective dogs, move them outward, so as to disengage from the cones or teeth b^{os} upon the pins b^{os} , and permit the pins to be moved back to their original positions by their springs b^{os} . In order to operate this bar, I provide a pin b^{os} , Figs. 2 and 13, extending sidewise from the end of the bar b^{os} outside the end frame X of the machine, which pin extends into a spiral cam-groove in the hub b^{os} of a tilting frame b^{os} , Fig. 6. The hub b^{os} bears against the end frame X, and when the frame b^{os} is tilted the bar b^{os} will be moved endwise. The frame b^{os} carries upon it two rollers, which are adapted to engage with a tilting yoke b^{os} on the cam-plate ω for operating the same. This yoke b^{os} is pivoted upon the cam-frame and is pulled in one direction by a spring b^{os} , so that the yoke rests against a stationary stop or pin b^{os} on the cam-frame. When the cam-frame ω moves in the positive direction, the yoke b^{os} passes over the tilting frame without actuating it; but when the cam-plate is moved in the return or negative direction one arm of the yoke engages with one of the rollers on the tilting frame b^{os} , tilts the frame partially, thus causing the other roller to enter in between the arms of the yoke, and, the movement of the yoke still continuing, the second arm of the yoke engages the other roller of the tilting frame and causes a further tilting of the tilting frame. The employment of the two rollers and of the yoke causes a greater arc of movement of the tilting frame, and thus a greater longitudinal movement of the 130

bar b^{18} for releasing the universal dogs. This could be the case if a single roller on the tilting frame and a single bar (instead of the yoke) were employed; but the double construction seems preferable. The tilting frame is carried back to its initial position by a suitable spring b^{25} .

The foregoing describes all the movements which relate to the computing operations in each of the denominations, but does not include the carrying mechanisms, which are now to be described.

Each ball-wheel B' carries a carrying-lever E , having a changeable fulcrum, and which is curved to conform to the circular form of the ball-wheel and is connected to said ball-wheel by means of a guide-stem E' , resting and adapted to slide in a slotted block e' , fastened upon the ball-wheel. (See Fig. 11.) The lever about at its middle is pivoted at e to the guide-stem, and thus may tilt upon the stem. The lower end of the lever E is provided with a pin e^2 , that extends into the groove B in the ball-wheel B' so far as to check and retain any balls which drop against said pin. At or near the pivotal point of the carrying-lever upon the stem is another pin e^3 , adapted to move into the groove of the ball-wheel whenever the lever is depressed at its middle. This pin e^3 is placed at a position so far distant from the pin e^2 upon the end of the carrying-lever that when a number of balls rest upon the last-mentioned dog, representing the maximum of the denomination to which that ball-wheel relates, the pin e^3 at the middle of the lever will when depressed rest upon a ball, thus holding it in the groove, tilting the free end of the lever and lifting the pin e^2 at its end out of the groove and discharging all the balls below that one which is pinched or clamped by the pin e^3 at the middle of the lever.

The end of the lever opposite to that bearing the retaining-pin e^2 is operated by a universal carrying-frame F , that extends across the machine and to which is connected all the carrying-levers of the different denominations. This carrying-frame is moved at each operation of the machine and has a series of slots f , Fig. 2, parallel to the lines of movement of the carrying-levers, and a screw or bolt e^4 passes through each slot f and into the block upon the end of the corresponding carrying-lever. It is now obvious that when any ball-wheel is moved its carrying-lever E is oscillated with it and the bolt or screw e^4 moves along the slot f in the carrying-frame.

The carrying-frame is operated at each movement of the machine by devices upon the cam-frames $x x'$, above described. From the ends of the carrying-frame there project outwardly through openings in the end frames $X X'$ pins f' , carrying friction-rollers f'' . (See Figs. 6 and 7.) These friction-rollers are in the paths of swinging cams f^3 , Figs. 6 and 7, carried by the cam-plates $x x'$. These carry-

ing-frame cams f^3 are normally held inward against the cam-plates by springs f^4 and are pivoted to the cam-plates, so as to swing to and from them. Each swinging cam has an inclined cam-surface f^5 , which at the first portion of the stroke of the cam-plate quickly depresses the carrying-frame, and continuous with these inclined surfaces are surfaces f^6 concentric with the cam-plate, whereby the roller f'' and carrying-frame F are first depressed and then are held in the depressed position through the forward positive stroke of the cam-frame. At the end of the forward stroke of the cam-frame a bunter f^7 on the end frame $X X'$ acts upon the end of the swinging cam, compressing the spring f^4 of the swinging cam and forcing the cam from engagement with the friction-roller.

Suitable springs f^8 raise the carrying-frame to its normal position as soon as this release occurs, and the movement of the carrying-frame brings the rollers f'' behind the swinging cam, so that the cam presses against the outer end of its roller during its return movement and until the inclined portion of the swinging cam permits it to pass the edge of the roller, whereupon the spring f^4 carries the cam back to its initial position.

Each carrying-lever E is connected by a link e^5 to one arm of a bell-crank lever e^6 upon its ball-wheel B' . The other arm of said bell-crank lever e^6 has a pin e^7 projecting therefrom and into a position adjacent to the wheel of the next higher denomination. The bell-crank levers are moved to their normal positions by springs e^8 , which tend to pull the free ends of the carrying-levers inward toward their ball-wheels and to set the pins e^7 on the ends of the said carrying-levers in the ball-grooves of the wheels.

Upon each ball-wheel is a sliding plate G , (see Figs. 9 and 11,) through which the hub B^2 of the wheel B' passes. The perforation g through the plate G , which encompasses the hub B^2 of the wheel, is an elongated slot, so as to permit the radial movement of the plate upon the wheel. A guide-pin g' , passing through an elongated radial slot g^2 in the plate and into the wheel, acts as further guiding means for the movement of said plate. Each plate has at its upper end a curved slot g^3 , that is cut upon a radius drawn from the center of the wheel, and into which the pin e^7 of the bell-crank lever e^6 of the wheel B' of the next lower denomination constantly projects. Consequently whenever the free end of the carrying-lever E is moved outward or away from the center of its wheel the plate G upon the wheel of the next higher denomination is moved downward. Upon the universal bar C is pivoted a movable block c' for each operating-wheel of the machine. This block is adapted to be moved in front of the universal bar C and has an end of such size that when upon movement of the universal

bar the end of the block comes in contact with a pin or with the end of the slot in the wheel through which the dog moves it will move said wheel one ball-diameter more than its normal movement, or if no pin is set it will move the wheel through one ball-space. This block is operated by a pin c^2 , extending therefrom into a curved slot g^4 in the sliding plate G of its denomination, so that when the free end 5 of a carrying-lever E is moved outward the link c^3 and bell-crank lever c^4 upon the wheel B' of any denomination operates the sliding plate G upon the wheel of the next higher denomination, and the block c^4 is moved into 10 the path of the universal bar C , so as to add or carry one ball in the groove B of said higher denomination. It will thus be seen that whenever balls representing the maximum of any denomination have accumulated upon the pin 15 c^2 at the end of the carrying-lever the pin c^3 at the middle of the carrying-lever on depression of the carrying-frame F tilts the carrying-lever and pinches the operating or dead ball Y' , representing said maximum, 20 (see Fig. 11,) lifts the free end of the carrying-lever, discharges all the balls beneath the pinched ball, and one ball is carried into the registering portion of the ball-groove of the wheel of the next higher denomination. Of 25 course this one ball represents the value of the balls discharged in the wheel of the next lower denomination.

The carrying operation always occurs upon the operation of the machine next succeeding 30 the operation by which the balls equal to or exceeding the maximum of any denomination are accumulated in the ball-groove of the denomination.

It is obvious that it is convenient and best 35 that the ball-wheels should always be set in order to return to their normal positions of rest, so that the dog b^4 , that holds the balls stationary during the return of the ball-wheels, may enter exactly between the balls and not 40 strike upon any, and for this purpose I provide a centering and locking device as follows: Upon each wheel B' is a series of ratchet-teeth B^3 , and across the whole series of wheels is a bar B^4 , having a sharpened edge adapted 45 to move into the spaces between said ratchet-teeth. These teeth are accurately spaced and beveled and placed so that when said bar enters the spaces between the teeth to its full depth the wheel is exactly centered for the 50 purpose above described. The bar B^4 is hung by arms B^5 upon a rod B^6 , passing through and journaled in the end plates $X X'$, and the bar normally pulled inward toward the ratchet-teeth by one or more springs (not shown) fastened to the arms and to the end plates of the 55 machine. The locking and centering bar B^4 is moved by a cam x^7 , Fig. 6, upon a cam-plate x at one end of the machine, engaging with an arm B^7 , fastened to the rod upon 60 which the locking-bar is hung. The arm B^7

last mentioned preferably bears a friction-roller that runs over the cam, and the bar is thus moved inward and outward at such times and for such periods as may be found desirable. This centering device also brings 70 the pins b^{10} of the pin-frames into their proper positions with reference to the ends a^{10} of the key-bars.

The locking-bar is engaged with the ratchets in the normal position of rest of the machine, as shown in Figs. 8 and 9, and is not lifted out therefrom until after the stirrup A^3 has risen and set the pins. The locking-bar B^4 is kept out of engagement with the latch until the end of the positive stroke of the 80 power device or handle, at which time it is thrown into locking engagement, thus holding the ball-wheels in position for the stationary dogs b^4 to hold the balls stationary while the wheels are returned. During the 85 negative or return stroke of the power device or handle the locking-bar is lifted out of its engagement with the ratchets and is held out of engagement until near the end of the return or negative stroke of the handle. 90 The purpose of this timing of the parts is to permit the movement and return of the ball-wheels to center the ball-wheels at the beginning of the positive stroke in order to cause the proper setting of all the parts connected 95 with the ball-wheels for the position of rest and to set all these parts accurately at the end of the positive stroke of the handle for a like purpose.

I employ a cam x^7 , as above stated, for operating the locking-bar, and this cam is sufficient for the purpose; but in order to produce a longer disengagement of the bar from the ratchets and a quicker engagement of said bar therewith I may employ a supplementary 100 device consisting of a double-acting stop B^8 , pivoted to the end plate x' , Fig. 7, of the frame and adapted to be tilted in each direction about its pivot by contact arms or stops $x^8 x^{10}$ upon the cam-plate. This stop is always pulled by a spring b^8 , that tends to bring it to a central position and to set its outer end under the arm or extension b^{10} of the locking-bar, whereby the locking-bar is held away 105 from the ratchets; but upon the stop being 110 struck by either of the contacts on the cam-plate the stop is tilted, releasing the bar therefrom and permitting it to drop quickly into the ratchets.

The full operation of the combination of 115 the cam and stop on the locking-bar is as follows: In the position of rest the stop B^8 rests upon the upper side of the arm or extension b^{10} of the locking-bar, as shown in Fig. 7, having been tilted into this position by one of the 120 contacts, x^8 , upon the cam-plate x' . On the positive stroke of the handle the cam x^7 lifts the locking-bar B^4 out of engagement with the ratchets B^3 , and at the same time the spring b^8 upon the stop B^8 brings it under the 125 130

arm b^{40} of the locking-bar, so that as the motion of the handle progresses the locking-bar drops upon the outer end of the stop B^8 , and thus remains out of contact with the ratchets 5 until the other contact, x^{80} , upon the cam-plate x' tilts the stop, moves it out from under the bar, and permits the bar to drop suddenly. On the return stroke the cam x' again lifts the locking-bar out of the ratchets, the stop 10 is brought by its spring underneath the locking-bar, the locking-bar rests upon the end of the stop and out of engagement with the ratchets, and at the end of the stroke the contact x^8 on the cam-plate tilts the stop and permits the locking-bar to fly in. This stop device, while convenient, is not necessary to the 15 operation of my machine.

Upon each cam-plate x and x' is pivoted a tilting cam x^{30} , normally held against a stop 20 x^{33} by a spring x^{32} . This cam x^{30} acts upon the roller a^{32} on one end of the bell-crank lever a^{30} , that raises the stirrup A^3 for lifting the setting-bars A , that act upon the pins b^{10} of the pin-frame. This cam x^{30} acts to lift the 25 stirrup A^3 as quickly as possible after the handle starts and rests against its pin in order to produce a positive and powerful action. On the return stroke, however, the cam x^{30} tilts and passes the roller a^{32} without moving the 30 bell-crank a^{30} .

In order to repeat a computing operation of the machine, I place upon the bar b^{18} , that bears the pins b^{19} for releasing the universal dogs b^{15} of the pin-frames b , a crank b^{30} and a 35 link b^{31} , (see Figs. 7 and 13,) which are pulled in one direction by a spring b^{32} . To the end of the link b^{31} I attach one arm of a bell-crank lever b^{33} , the other arm of which is attached to the stem of a finger-piece A^4 , which passes 40 upward through the keyboard-plate of the machine. A notch a^4 in the stem of the key or finger-piece A^4 is adapted to engage the edge of the perforation in the keyboard-plate A^3 in order to hold the key-stem down and to 45 hold the crank b^{30} upon the bar b^{18} in its abnormal position. The spring b^{32} tends to pull the link in the other direction, and I provide a stop b^{34} upon the frame and a lug b^{35} upon the link, which in the position of rest are in 50 engagement with each other. On depressing the finger-piece and engaging the notch a^4 in its stem in the edge of the perforation in the keyboard-plate A^3 the bar b^{18} , carrying the pins b^{19} , is rotated through an arc sufficient to 55 move the pins out of any possible engagement with the universal dogs b^{15} , and consequently the pins b^{10} , that have been operated, remain raised, and the operation of the machine is repeated as many times as may be desired 60 and until the notch a^4 in the stem of the finger-piece is released and the finger-piece, link b^{31} , crank b^{30} , and rod b^{18} are returned to their normal positions by the spring b^{32} , that acts upon the link.

65 In order to reset the keys A^2 in case a wrong

key has been depressed, I provide a key A^6 , Fig. 1, extending up through the keyboard-plate A^5 and attached to one arm of a bell-crank lever a^6 , (see Fig. 6,) the other arm of which is attached to a link a^{60} , connecting with 70 a crank a^{61} upon the rod a^{61} , that bears the series of dogs A' for holding the longitudinally-movable setting-bars A in their set positions. A spring a^{62} , acting upon the link a^{60} , bell-crank lever, or key-stem, tends to retain these 75 parts in a normal position; but when the key-stem A^6 is depressed the rod a^{61} , carrying the series of dogs, is turned, and all the dogs are moved out of engagement with the setting-bars, permitting the latter to return to their 80 normal positions of rest by the operations of the springs a .

At each operation of the machine a pin x^{60} on the cam-plate x (see Fig. 6) strikes a lever a^{63} on the bar a^{61} , tilts the bar, and releases 85 all the dogs A' from the operated setting-bars A . The bars are returned to their initial positions, as just described. I thus provide for an automatic and a non-automatic resetting of the operated keys.

In order to reset the machine to zero, I provide a bar H , running across the machine through openings in the upper portions of the ball-wheels and journaled in the end plates $X X'$ and provided with a series of arms h , 90 having projecting studs h' , one for each ball-wheel, and adapted when the bar H is rotated to strike the tops of all the sliding plates G upon the ball-wheels and to depress them. A handle H' is provided on the outside of the 100 machine for operating this bar. Upon operating the handle H' and turning the bar H the sliding plates G are all depressed, and the carrying-levers E , through the bell-cranks e^1 and links e^5 , are moved outward from the periphery of the ball-wheels, thus lifting out the pins e^2 upon the carrying-levers and disengaging the balls, which rest upon said pins, 105 permitting the balls to run downward in the channel. This fills the vacant ball-spaces in 110 the registering-channel B^{10} below the pins e^2 up to their maximum. The same operation or depression of the sliding plates G moves the dogs c' in front of the universal bar C and upon operation of the machine brings one ball 115 from the stored balls in the back of each wheel into the channel B in front to be caught and held upon the pins e^2 on the ends of the carrying-levers E .

It is well known from my prior patents relating to ball-registers, as set forth in my prior patents and applications, that a dead-ball or an eleventh ball is always employed as an operating-ball and not for computing. Thus operating the machine while holding the 120 handle H' in its turned position the sliding plates G are actuated, and the registering portions B^{10} of the ball-channels are filled, and the dead-ball is replaced on the pins e^2 of each ball-wheel, and thus the machine is reset to 125 130

zero, it being observed, however, that in this 5 operation of resetting to zero the handle H' is held turned long enough only to hold the plates G depressed until the universal bar C , with its depressed dogs c' , can move each of the ball-wheels simultaneously one space, and thus force forward the dead-ball for each wheel, whereupon the handle H' is immediately released to permit the plates G , and therefore the carrying-levers E , to be returned to normal position, with the pins e^2 returned into the ball-channels in time to arrest the dead-balls, this being the normal zero condition of the machine, as shown in Fig. 9.

15 Having now described the setting and registering mechanisms, the resetting mechanism, and the repeating mechanism, the remainder of the machine consists in a printing mechanism for printing the amount of each operation of the machine and a mechanism for printing the sum-total of the several amounts theretofore registered and printed.

The printing mechanism consists, broadly, of a series of type-carriers, an impression mechanism, a platen-setting mechanism, and a paper-feed mechanism. These mechanisms are all operated by the same power device or handle which operates the registering devices in the machine.

30 The type-carriers are set by the movements of the ball-wheels and proportionately to the movements thereof. In the case of a carrying operation performed by any ball-wheel the setting of the type-carrier must differ from 35 the setting of the ball-wheel, and provision is made that under those circumstances the type-carrier is set in the same manner as if no carrying were occurring.

The type-carriers are all set normally to 40 print zero at the printing-line, and in order to prevent the printing of the zeros in denominations above that of the highest ball-wheel which is set I provide a movable platen, which is at every operation of the machine 45 moved transversely to the line of print and in a direction beginning with the lowest denomination and so far as to register with only those type-carriers that have been set in consequence of the setting operations of 50 the machine. With this system of operating the platen the ciphers of higher denominations than any set-key will not be printed.

The type-carriers in the present embodiment of my invention consist of a series of 55 segments J , (see Figs. 8 and 9,) one for each denomination, pivoted upon a table or cross-plate Z , resting upon the end plates $X X'$ of the machine. The type-segments have type j on their peripheries and are capable of oscillation in vertical planes, being hung on a bar J' , set transversely of the machine and in the upper part thereof. Each type-segment is connected to an arm or lug j^2 by suitable links j' , (see Fig. 8,) which are bent in the 60 present instance, as shown in Fig. 14, in or-

der to permit the connection from the widely-separated ball-wheels B' to the more narrowly and compactly arranged type-segments. These links j' might be directly pivoted to their ball-wheels; but for certain reasons, 70 which will be developed later, each link is connected to an arm or lever j^2 , which is hung upon a hub of each ball-wheel B' and incapable of oscillation with reference thereto. A side arm or extension j^3 from said lever j^2 75 normally rests against a pin g^5 , projecting from the sliding plate G of the ball-wheel B' of that denomination, so that when the ball-wheel is moved to perform a registering operation the lever is moved to a corresponding 80 degree, and thereby the type-carrier is set with a type at the printing-line corresponding to the value registered upon that ball-wheel. If, however, a carrying operation is occurring upon that ball-wheel and 85 the sliding plate G is lowered, as above described, the pin g^5 upon the sliding plate moves out of possible engagement with the side arm or extension j^3 of the lever, and another pin, b^5 , upon the ball-wheel B' comes in 90 contact with the lever and moves it to set the correct type on the type-carrier. On account of the extra motion of the ball-plate that occurs in a carrying operation it becomes necessary to reduce the movement of the lever 95 j^2 , that controls the operation of the type-segments, to an arc less than that of the movement of the ball-wheel by exactly the amount of that extra carrying movement, and therefore while the pin g^5 upon the sliding plate 100 G is normally in contact with the side arm or extension j^3 of the lever j^2 , that operates the type-carriers, the pin b^5 upon the ball-wheel B' is set in such a position that the ball-wheel must move to an extent equal to one type-space upon the periphery of the type-carrier before this pin meets the lever and moves it. The links j' are of course pivoted to the type-segments J in any suitable way. A convenient mode of pivoting a link to a type-carrier 110 is to form a large head j^0 , Figs. 8 and 9, on the end of the link and to set the head j^0 in a somewhat larger perforation through the type-carrier. A narrowed portion of said perforation, however, passes around the large 115 head j^0 of the link. The head j^0 is held in place by means of thin plates j^{00} , fastened upon the sides of the type-carrier, and encloses the head j^0 in the perforation.

The inking-ribbon K^0 passes in a well-known manner across the faces of the type-carriers J and is provided with suitable guides k^0 to keep it in proper relation to the type. Various mechanisms may be employed for feeding fresh portions of the ribbon to the printing-line; but a convenient device for this purpose is now to be described. I provide two drums $K K'$, on which the two ends of the ribbon K^0 are rolled. Said drums are revoluble upon axles $k k'$ at right angles to 130

the plane of movement of the ribbon. Automatic devices operate one or the other of these drums, as desired, to cause them to act correspondingly and to cause a gradual feed of the ribbon across the type. Upon the axle of each drum K K', Figs. 3 and 4, is placed a ratchet-wheel k^2 and an arm k^3 , capable of oscillation upon said axle, and upon the arm is a spring-actuated driving-pawl k^4 , adapted to engage with the ratchet-wheel and to cause its rotation when the arm is oscillated. Another pawl k^5 , pivoted upon a stationary support, is normally held in engagement with its ratchet-wheel by a spring for the purpose of preventing backward rotation of the ratchet-wheel and drum. The arms carrying the driving-pawls k^4 are connected together by a link k^6 , and said link is connected to a driving-bar k^7 , held in suitable guides underneath the type-plate of the machine and normally pulled in one direction by a spring k^8 , Fig. 2. The connection between the driving-bar k^7 and the link k^6 is a pin k^9 , Fig. 1, upon said driving-bar and extending through a slot k^{10} in the top plate Z and into a socket or perforation in an arm k^{11} , carried by the link. The driving-bar k^7 is operated by a lever k^{12} , Fig. 2, pivoted on one of the end plates of the machine and having one end pivoted to the end of the driving-bar and the other end in the path of a cam x^{20} , Figs. 2 and 6, upon one of the cam-plates. Whenever the machine is operated, the cam-plate oscillates, the cam x^{20} operates the lever k^{12} , which moves the driving-bar k^7 and puts its spring k^8 in tension, moves the link k^6 and the pawls k^4 on the arms k^3 , and drives the ratchet-wheels k^2 and the drums K K' in a manner hereinafter explained. When the cam x^{20} on the cam-plate is disengaged from the lever k^{12} , the spring k^8 , connected to the driving-bar k^7 , returns the parts to their initial positions.

I will be noticed that the ribbon K⁰ is wound upon the two drums K K' in the same direction, and consequently the two drums may revolve in the same rotary direction whichever one of them winds the ribbon upon it provided the other drum is free to revolve without action of the pawls. In order to disengage the pawls k^4 k^5 from one or the other of the wheels, as may be desired, I provide a cam-plate k^{13} , set free upon each of the drum-axes k k' , which when turned to the proper position holds both dogs related to that drum away from the ratchet-wheel; but by means of depressions or notches therein when the cam k^{13} is turned the pawls k^4 k^5 may rest in the teeth of the ratchet-wheel k^2 . In order to turn these cams alternately, so that when one excludes the dogs from operation upon its ratchet-wheel the other permits the dogs to engage the ratchet-wheel, I provide a bar k^{14} , movable in suitable guides k^{15} on the top plate Z and pivoted to an arm k^{16} of each of said cam-plates, the arms k^{16} and pivotal

points being so adjusted that when one cam is in operation the other is not. The bar k^{14} , just described, is set into one or the other of its positions by means of a lever k^{17} , supported upon the top plate Z of the machine and operated by a suitable finger-piece k^{18} . The lever k^{17} moves horizontally and engages in a notch k^{19} in said bar, so that when the lever is turned into its positions the bar follows.

The platen-frame L is fixed upon a cross-rod or shaft L', which is journaled in the end plates X X' of the machine and is operated by a lever-arm l, Fig. 7, on said shaft L', a link l', connected with said arm, a second link l'', connected at one end to the link l' and pivoted at the other end at l''' to the end plate X'. A spring l⁴ pulls the arm l in a manner to move the platen-frame normally away from the type-segments J. A tripping-dog l⁵ is pivoted upon the cam-plate x' and is normally held against a stop l⁶ on said plate by a suitable spring l⁷, so that when the cam-plate is moving in the positive direction the dog passes freely over a pin or roller l⁸ upon one of the links connected to the platen-shaft, (the link l'') but when the cam-plate moves in the negative direction the dog l⁵ strikes solidly against the pin or roller l⁸ and moves the link, so as to tilt the platen-shaft, and with it the platen-support and platen, to make a printing impression against the type. If it is not desired to omit the unnecessary ciphers from a printed line, the platen may be a stationary platen fixed on the platen-frame L, and the paper is pressed by the platen against the inking-ribbon, through which the type makes an impression in the usual manner.

In order to center and hold the type-carriers J in their proper positions, I provide a centering and locking bar j¹⁰, (see Figs. 8 and 9,) fixed upon the platen-shaft L' by the arms j¹¹ and having a sharpened edge, whereby it is adapted to enter between ratchet-like teeth j¹² upon the type-carrier. For convenience of arrangement these teeth are cut in and through the type-carrier in a line concentric with and back of the periphery and have between their pointed extremities and the adjacent solid portion of the type-carrier a slot 115 whereby the type-carrier J may oscillate. While the locking-bar j¹⁰ is tilted by the oscillation of the platen-shaft the locking-bar enters between the sharpened teeth on the type-carriers, holding those which are set in their set positions and also holding those which are not set in their unoperated positions.

The platen-operating mechanism is so set as to operate at the first portion of the return stroke of the power device or handle, so that the printing impression occurs before it becomes necessary to move any of the parts of the machine in order to return them to their initial positions. The locking-bar for the type-segments moves with the platen and sub-

stantially alternately with the locking-bar B^4 for the ball-wheels. The locking-bar B^4 for the ball-wheels is in engagement with the ratchets B^3 upon the ball-wheels B' at the beginning of the return stroke and is quickly lifted out therefrom soon after the beginning of the stroke. As this locking-bar B^4 moves out the other locking-bar, j^{10} , moves into engagement with the teeth j^{12} of the type-segments J and disengages therefrom immediately after the printing impression occurs.

Upon the platen-support is a transversely-movable platen L^2 , (see Figs. 5, 7, and 8,) which is set in guides L^4 upon a block L^3 , movable crosswise of the machine and parallel to the line of print and supported by the platen-frame L . In the normal position of rest the platen proper, L^2 , is at one side of printing position, so that if the platen-support is rocked the platen is not in position to make an impression against any of the type; but when a key is operated relating, say, to the first or unit denomination the platen is set so that a portion of its surface is placed in front of the units type-carrier, but is not moved so far as to be in front of any of the other type-carriers. If, again, a key is operated in the bank relating to thousands, the platen is moved so far as to come in front of all the type-carriers up to and including that one representing thousands, but is not moved out so far as to come in front of any of the other type-carriers of higher denominations than thousands. The platen is moved in the present instance by means of a link L^5 , a bell-crank lever L^6 , pivoted on the platen-frame L , and a second link L^7 , (see Figs. 5 and 7,) extending to a bail-like device, which will now be described. This bail-like device consists of a bar L^{10} , (see Figs. 5 and 7,) extending across the back of the machine and attached at its ends to arms L^{11} , hung on the ends of the driving-shaft and outside of the end plates and cam-plates. The bar L^{10} is normally pulled in an upward direction by means of suitable springs L^{12} . This bar rests close to the back edges of the whole set of ball-wheels. Upon a transverse shaft L^8 , (see Fig. 8,) adjacent and parallel to said bar and supported by the end plates of the machine, are a series of stop-levers L^{14} , one for each ball-wheel and normally drawn rearward by springs L^{13} . A stop L^{14} (see Fig. 8) upon each lever L^{14} projects into the path of movement of the transverse bar L^{10} , and the stops L^{14} are set at graded distances from the normal position of rest of said bar proportionate to the amount of motion necessary to be imparted to the platen to carry it to the proper position for printing the highest denomination for which a key has been set. These stop-levers L^{14} have cam-slots L^{14} , Fig. 8, in them, into which project pins j^{20} upon the levers j^2 , before described, which operate the links for setting the type-segments. The first movement of any one of

said levers j^2 pulls in its stop-lever out of the way of the bail-bar. For instance, if keys in the tens and units columns are operated the stop-levers related to these columns are pulled in and the bail rises under the influence of its springs L^{12} until it strikes against the stop-lever relating to the hundreds denomination. The parts are so adjusted that this movement of the bar L^{10} through the connection of the link L^7 with the arm L^{11} (see Fig. 8) moves the platen in front of the type-carriers relating to the tens and units, but not in front of the hundreds or other type-carriers of higher denominations. In order that this operation of the platen should be entirely automatic, I provide a series of overlapping lugs L^{11} , Fig. 10, upon said stop-levers L^{14} , which overlap from the lever of each lower denomination upon the lever of the next higher denomination throughout the whole series, so that if a key in any higher denomination is operated and the machine is actuated the stop-levers of all lower denominations will be retracted and moved out of the way of the bail-bar L^{10} , allowing it to rise freely to strike the stop of the denomination next above the highest denomination in which a key has been operated, and so setting the platen as above described. It is obvious that in this way the movable platen is set so as to omit the printing of the ciphers above any denomination in which a key has been operated, although the ciphers upon the type-carriers are normally set at the printing-line. The bail-bar is carried back to normal position by means of the pin w^3 upon the cam-plate.

A paper strip W is employed to receive the impression from the type, which strip is drawn from a reel W' , suitably supported at the back of the machine. The paper-feeding mechanism consists of two rollers w^1 , set transversely across the machine at the back thereof, geared together at one end and operated at the other end by an ordinary ratchet clutch movement. The ratchet movement may be operated by an arm w^2 , extending from the axle of a ratchet-wheel w^3 on one of the rollers and bearing a pawl w^4 for engagement with said ratchet-wheel. The arm w^2 extends into the paths of a pin w^5 upon the cam-plate w , which operates the device to cause rotation of one of the rollers, and a spring w^6 tilts the arm back to initial position.

The printing device thus far described prints the amount corresponding to the keys depressed at a single operation of the machine; but in this machine there is added to this a mechanism for printing the answer or sum-total of a series of single registering operations. The general principle of this device for printing the sum-total is that when the balls in the registering portions B^{10} of the channels indicate a certain sum according to the heights of the respective columns if the type-carriers are moved to positions corre-

sponding to the heights of the respective columns an impression may be made which gives the sum-total or answer of all the operations of the machine up to that time. In order to accomplish this purpose, I provide a series of answer-levers O , Fig. 8, one being journaled upon the hub of each ball-wheel and each provided with a spring o to pull it downward. A latch O' , pivoted upon each ball-wheel, engages with a proper hook o' or shoulder upon the answer-lever O to retain it in the raised position. An angle-lever O^2 is pivoted upon the answer-lever and is provided with a tooth or point adapted to be moved into the ball-groove of its wheel by a spring o^2 . When the lever is latched in the raised position, as just described, the angle-lever O^2 is pressed against a stop o^4 , mounted on the adjacent ball-wheel, which stop tilts the lever O^2 and lifts the pin or dog o^3 on the angle-lever (see Fig. 8) out of the ball-wheel and retains it in this position against the tension of the spring o^2 , which acts upon said lever and tends to pull the dog into the ball-groove. If now the latch is released, the spring o^2 on the angle-lever immediately pulls the pin o^3 into the ball-groove, while the spring o upon the answer-lever O pulls the lever downward until it is stopped by contact of its dog against the type-ball in the column below it. The balls are so adjusted in number and by the retaining-dogs b' on the ball-wheels that there is always a slight vacancy above a normally full column in order to permit the dog o^3 on the answer-lever O to pass freely into the ball-groove B . The end of each answer-lever opposite to the end carrying the dogs o^3 is connected with the lever j^2 , that sets the type-segments by a loose pin-and-slot connection, which is loose just to the extent necessary to permit the dog o^3 to snap into the ball-groove. In order that all the latches O' for releasing the answer-levers may move at once, a bar P is provided running across the whole machine, which is carried upon side arms p , pivoted to the side plates $x x'$. This bar extends in close proximity to the tails of the latches O' of the answer-levers O , so that when the bar is depressed by its handle P' , projecting from the front of the case of the machine, all the latches are tilted and the answer-levers released, whereby all the answer-levers are pulled down by their impelling-springs until they rest upon the tops of the ball-columns of the various ball-wheels. This movement of the answer-levers, as just described, raises the levers which control the links connected in the type-segments, the type-segments are set, and upon operation of the power device or handle the answer is printed.

When the machine is in zero condition, as shown in Figs. 8 and 9, with the single dead ball resting upon each of the pins e^2 , as explained hereinbefore, it will be noticed that the ball-channels below the pins e^2 are filled to

such an extent that when the dogs o^3 on the answer-levers O are released for striking the total they will enter the ball-channels and rest upon the top ball of each column, so that the answer-levers O will not fall, and therefore the type-segments will not be moved, and if the printer is operated in this position a row of zeros will be printed.

Indicators O^4 on the ends of the answer-levers O extend through slots o^4 in the front casing of the machine, and scales O^5 , adjacent to said slots, afford means of reading the sum-total or answer whenever the handle P' is operated to release the latches.

The answer-levers O may be returned to initial position by hand by lifting the indicators O^4 .

What I claim is—

1. The combination, in a computing-machine, of a registering device; a setting mechanism, consisting of a movable frame, having a series of movable parts for determining the extent of movement of the registering device; a series of key-operated devices, each, when operated, adapted to make contact with a movable part of said setting device; means for moving the series of key-operated devices to make contact between an operated device and its said movable part for actuating the latter; and an operating mechanism for actuating said setting device for operating the registering device.

2. The combination, in a computing-machine, of a movable registering device; a setting mechanism, movable with said registering device and consisting of a movable frame having a series of movable parts for determining the extent of movement of said registering device; a series of key-operated devices, each, when operated, adapted to make contact with a movable part of said setting device; means for moving the series of key-operated devices to make contact between an operated device and its said movable part for actuating the latter; and an operating mechanism for actuating said setting device for operating the registering device.

3. The combination, in a computing-machine, of a movable registering device; a setting mechanism consisting of a frame carried by said registering device and having a series of movable pins for determining the extent of movement of said registering device; a series of key-operated devices, each, when operated, adapted to make contact with a particular pin of said setting device; means for moving the series of key-operated devices to make contact between an operated device and its pin for moving the latter; and an operating mechanism comprising a swinging bar for operating said registering device by striking the pins actuated as aforesaid.

4. In a computing-machine, the combination of a circular guideway or channel for balls; balls for said guideway; means for moving

said balls in said guideway, comprising a setting mechanism consisting of a frame having a series of movable parts for determining the extent of movement of said balls; a series of 5 key-operated devices, each, when operated, adapted to make contact with a particular movable part of said setting mechanism; means for moving the series of key-operated devices to make contact between an operated 10 device and its said movable part for actuating the latter; and an operating mechanism for moving said setting devices by means of an actuated movable part for operating the balls.

5. In a computing-machine, the combination 15 of a wheel having a guideway for balls in its periphery; a setting mechanism carried by said wheel and consisting of a frame having a series of movable parts for determining the extent of movement of said wheel; a series 20 of key-operated devices, each, when operated, adapted to make contact with a particular movable part of said setting mechanism; means for moving the series of key-operated devices to make contact between an operated 25 device and its said movable part for actuating the latter; and an operating mechanism comprising a swinging bar for actuating said wheel by striking said actuated movable part and moving the wheel thereby.

30 6. In a computing-machine, the combination of a wheel having a guideway for balls in its periphery; balls for said guideway; a setting mechanism carried by said wheel and consisting 35 of a frame having a series of movable parts for determining the extent of movement of said wheel; a series of key-operated devices each, when operated, adapted to make contact with a particular movable part of said setting mechanism; means for moving the series 40 of key-operated devices to make contact between an operated device and its said movable part for actuating the latter; an operating mechanism, comprising a swinging bar for actuating said wheel by striking said actuated movable part and moving the wheel 45 thereby; means, for moving the balls with the wheel; and means, operated from said motor mechanism, for holding said balls, while said wheel is returned to initial position.

50 7. The combination, in a computing-machine, of a registering device; a setting mechanism, consisting of a movable frame, having a series of movable parts for determining the extent of movement of the registering device; a series of key-operated devices, each having a setting movement and an operating movement and each, when operated, adapted to make contact with a movable part of said setting device; means for moving the series 55 of key-operated devices to make contact between an operated device and its said movable part for actuating the latter; and an operating mechanism for actuating said setting device for operating the registering device.

65 8. The combination, in a computing-ma-

chine, of a movable registering device; a setting mechanism, movable with said registering device and consisting of a movable frame having a series of movable parts for determining the extent of movement of said registering device; a series of key-operated devices, each having a setting movement and an operating movement and each, when operated, adapted to make contact with a movable part of said setting device; means for moving the series of key-operated devices to make contact between an operated device and its said movable part for actuating the latter; and an operating mechanism for actuating said setting device for operating the registering device.

9. The combination, in a computing-machine, of a movable registering device; a setting mechanism consisting of a frame carried by said registering device and having a series 85 of movable pins for determining the extent of movement of said registering device; a series of key-operated devices, each having a setting movement and an operating movement and each, when operated, adapted to make 90 contact with a particular pin of said setting device; means for moving the series of key-operated devices to make contact between an operated device and its pin for moving the latter; and an operating mechanism comprising a swinging bar for operating said registering device by striking the pins actuated as aforesaid.

10. In a computing-machine, the combination of a circular guideway or channel for balls; balls for said guideway; means for moving said balls in said guideway, comprising a setting mechanism consisting of a frame having a series of movable parts, for determining the extent of movement of said balls; a series of key-operated devices, each having a setting movement and an operating movement and each, when operated, adapted to make contact with a particular movable part of said setting mechanism; means for moving the series of key-operated devices to make contact between an operated device and its said movable part for actuating the latter; and an operating mechanism for moving said setting devices by means of an actuated movable part 115 for operating the balls.

11. In a computing-machine, the combination of a wheel having a guideway for balls in its periphery; a setting mechanism carried by said wheel and consisting of a frame having a 120 series of movable parts for determining the extent of movement of said wheel; a series of key-operated devices, each having a setting movement and an operating movement and each, when operated, adapted to make contact 125 with a particular movable part of said setting mechanism; means for moving the series of key-operated devices to make contact between an operated device and its said movable part for actuating the latter; and an operating 130 mechanism for actuating the latter; and an operating

mechanism comprising a swinging bar for actuating said wheel by striking said actuated movable part and moving the wheel thereby.

12. In a computing-machine, the combination of a wheel having a guideway for balls in its periphery; balls for said guideway, a setting mechanism carried by said wheel and consisting of a frame having a series of movable parts for determining the extent of movement of said wheel; a series of key-operated devices, each having a setting movement and an operating movement and each, when operated, adapted to make contact with a particular movable part of said setting mechanism; means for moving the series of key-operated devices to make contact between an operated device and its said movable part for actuating the latter; an operating mechanism, comprising a swinging bar for actuating said wheel by striking said actuated movable part and moving the wheel thereby; means, as a dog, for moving the balls with the wheel; and means, as another dog, operated from said operating mechanism, for holding said balls while said wheel is returned to initial position.

13. In a computing-machine, the combination of an oscillating ball-wheel having a guideway or channel for balls; balls for said guideway, means for moving the balls with the wheel in one direction; means for preventing movement of the balls with the wheel in the other direction; setting mechanism for determining the degree of oscillation of said wheel; and an operating mechanism for moving said wheels correspondingly to said setting mechanism and for returning said wheels to initial position.

14. In a computing-machine, the combination of two oscillating ball-wheels representing different denominations, and each having a guideway or channel for balls; balls for said guideway; means on each wheel for moving the balls with the wheel in one direction; means for preventing movement of the balls with a wheel in the other direction; setting mechanism for determining the degree of oscillation of each wheel; an operating mechanism common to said wheels for moving each wheel correspondingly to its setting mechanism and for returning said wheels to their initial positions; and a carrying mechanism between said wheels operated by said operating mechanism for moving a ball in the channel of the wheel of higher denomination whenever a certain number of balls have accumulated in a particular portion of the channel of the wheel of lower denomination and for releasing the column of balls in the channel of lower denomination.

15. In a computing-machine, the combination of a circular guideway or channel for balls; balls for said guideway; means for moving said balls in said guideway, comprising a setting mechanism consisting of a frame having a series of movable parts for determining

the extent of movement of said balls; a series of key-operated devices, each, when operated, adapted to make contact with a particular movable part of said setting mechanism; means for moving the series of key-operated devices to make contact between an operated device and its said movable part for actuating the latter; an operating mechanism for moving said setting devices by means of an actuated movable part for operating the balls; an indicator-arm, for indicating the heights of the registering column of balls, normally held in non-indicating position; and means for releasing said arm at will to make contact with the top of said column.

16. In a computing-machine, the combination of a wheel having a guideway for balls in its periphery; balls for said guideway; a setting mechanism carried by said wheel and consisting of a frame having a series of movable parts for determining the extent of movement of said wheel; a series of key-operated devices, each, when operated, adapted to make contact with a particular movable part of said setting mechanism; means for moving the series of key-operated devices to make contact between an operating device and its said movable part for actuating the latter; an operating mechanism, comprising a swinging bar for actuating said wheel by striking said actuated movable part and moving the wheel thereby; means, as a dog, for moving the balls with the wheel; means, as another dog, operated from said operating mechanism, for holding said balls, while said wheel is returned to initial position; an indicator-arm, for indicating the heights of the registering column of balls, normally held in non-indicating position; and means for releasing said arm at will to make contact with the top of said column.

17. In a computing-machine, the combination of a circular guideway or channel for balls; balls for said guideway; means for moving said balls in said guideway, comprising a setting mechanism consisting of a frame having a series of movable parts, for determining the extent of movement of said balls; a series of key-operated devices, each having a setting movement and an operating movement and each, when operated, adapted to make contact with a particular movable part of said setting mechanism; means for moving the series of key-operated devices to make contact between an operated device and its said movable part for actuating the latter; an operating mechanism for moving said setting devices by means of an actuated movable part for operating the balls; an indicator-arm, for indicating the heights of the registering column of balls, normally held in non-indicating position; and means for releasing said arm at will to make contact with the top of said column.

18. In a computing-machine, the combina-

- tion of a wheel having a guideway for balls in its periphery; balls for said guideway; a setting mechanism carried by said wheel and consisting of a frame having a series of movable parts for determining the extent of movement of said wheel; a series of key-operated devices, each having a setting movement and an operating movement and each, when operated, adapted to make contact with a particular movable part of said setting mechanism; means for moving the series of key-operated devices to make contact between an operated device and its said movable part for actuating the latter; an operating mechanism comprising a swinging bar for actuating said wheel by striking said actuated movable part and moving the wheel thereby; an indicator-arm, for indicating the heights of the registering column of balls, normally held in non-indicating position; and means for releasing said arm at will to make contact with the top of said column.
19. In a computing-machine, the combination of a wheel having a guideway for balls in its periphery; balls for said guideway; a setting mechanism carried by said wheel and consisting of a frame having a series of movable parts for determining the extent of movement of said wheel; a series of key-operated devices, each having a setting movement and an operating movement and each, when operated, adapted to make contact with a particular movable part of said setting mechanism; means for moving the series of key-operated devices to make contact between an operated device and its said movable part for actuating the latter; an operating mechanism, comprising a swinging bar for actuating said wheel by striking said actuated movable part and moving the wheel thereby; means for moving the balls with the wheel; means operated from said operating mechanism, for holding said balls, while said wheel is returned to initial position; an indicator-arm, for indicating the heights of the registering column of balls, normally held in non-indicating position; means for releasing said arm at will to make contact with the top of said column; a printing mechanism; and a connection with said indicator-arm for setting the same.
20. In a computing-machine, the combination of a circular guideway or channel for balls; balls for said guideway; means for moving said balls in said guideway, comprising a setting mechanism consisting of a frame having a series of movable parts for determining the extent of movement of said balls; a series of key-operated devices, each, when operated, adapted to make contact with a particular movable part of said setting mechanism; means for moving the series of key-operated devices to make contact between an operated device and its said movable part for actuating the latter; an operating mechanism for moving said setting devices by means of an actuated movable part for operating the balls; an indicator-arm, for indicating the heights of the registering column of balls, normally held in non-indicating position; means for releasing said arm at will to make contact with the top of said column; a printing mechanism; and a connection with said indicator-arm for setting the same.
21. In a computing-machine, the combination of a wheel having a guideway for balls in its periphery; balls for said guideway; a setting mechanism carried by said wheel and consisting of a frame having a series of movable parts for determining the extent of movement of said wheel; a series of key-operated devices, each, when operated, adapted to make contact with a particular movable part of said setting mechanism; means for moving the series of key-operated devices to make contact between an operated device and its said movable part for actuating the latter; an operating mechanism, comprising a swinging bar for actuating said wheel by striking said actuated movable part and moving the wheel thereby; means for moving the balls with the wheel; means operated from said operating mechanism, for holding said balls, while said wheel is returned to initial position; an indicator-arm, for indicating the heights of the registering column of balls, normally held in non-indicating position; means for releasing said arm at will to make contact with the top of said column; a printing mechanism; and a connection with said indicator-arm for setting the same.
22. In a computing-machine, the combination of a circular guideway or channel for balls; balls for said guideway; means for moving said balls in said guideway, comprising a setting mechanism consisting of a frame having a series of movable parts, for determining the extent of movement of said balls; a series of key-operated devices, each having a setting movement and an operating movement and each, when operated, adapted to make contact with a particular movable part of said setting mechanism; means for moving the series of key-operated devices to make contact between an operated device and its said movable part for actuating the latter; an operating mechanism for moving said setting devices by means of an actuated movable part for operating the balls; an indicator-arm, for indicating the heights of the registering column of balls, normally held in non-indicating positions; means for releasing said arm at will to make contact with the top of said column; a printing mechanism; and a connection with said indicator-arm for setting the same.
23. In a computing-machine, the combination of a wheel having a guideway for balls in its periphery; balls for said guideway; a setting mechanism carried by said wheel and consisting of a frame having a series of movable parts for determining the extent of movement of said wheel; a series of key-operated devices,

each having a setting movement and an operating movement and each, when operated, adapted to make contact with a particular movable part of said setting mechanism; 5 means for moving the series of key-operated devices to make contact between an operated device and its said movable part for actuating the latter; an operating mechanism comprising a swinging bar for actuating said wheel 10 by striking said actuated movable part and moving the wheel thereby, an indicator-arm, for indicating the heights of the registering column of balls, normally held in non-indicating position; means for releasing said arm at 15 will to make contact with the top of said column; a printing mechanism; and a connection with said indicator-arm for setting the same.

24. In a computing-machine, the combination of a wheel having a guideway for balls in 20 its periphery; balls for said guideway; a setting mechanism carried by said wheel and consisting of a frame having a series of movable parts for determining the extent of movement of said wheel; a series of key-operated devices, each having a setting movement and an operating movement and each, when operated, adapted to make contact with a particular movable part of said setting mechanism; means for moving the series of key-operated devices 25 to make contact between an operated device and its said movable part for actuating the latter; an operating mechanism, comprising a swinging bar for actuating said wheel by striking said actuated movable part and moving the wheel thereby; and connections therewith for making the printing impression.

30 25. The combination, in a computing-machine, of a registering device, a setting mechanism, consisting of a movable frame, having a series of movable parts for determining the 35 extent of movement of the registering device; a series of key-operated devices, each, when operated, adapted to make contact with a movable part of said setting device; means for moving the series of key-operated devices to 40 make contact between an operated device and its said movable part for actuating the latter; a printing mechanism set by the registering device; an operating mechanism for actuating said setting device for operating the registering device; and connections therewith for 45 making the printing impression.

26. The combination, in a computing-machine, of a movable registering device; a setting mechanism consisting of a frame carried 50 by said registering device and having a se-

ries of movable pins for determining the extent of movement of said registering device; a series of key-operated devices, each, when operated, adapted to make contact with a particular pin of said setting device; means for 55 moving the series of key-operated devices to make contact between an operated device and its pin for moving the latter; a printing mechanism set by the registering device; an operating mechanism comprising a swinging bar 60 for operating said registering device by striking the pins actuated as aforesaid; and connections therewith for making the printing impression.

27. In a computing-machine, the combination of a wheel having a guideway for balls in 65 its periphery; balls for said guideway; a setting mechanism carried by said wheel and consisting of a frame having a series of movable parts for determining the extent of movement of said wheel; a series of key-operated devices, each, when operated, adapted to make contact with a particular movable part of said setting mechanism; means for moving the series of key-operated devices to make contact 70 between an operated device and its said movable part for actuating the latter; a printing mechanism set by said wheel; an operating mechanism comprising a swinging bar for actuating said wheel by striking said actuated 75 movable part and moving the wheel thereby; and connections therewith for making the printing impression.

28. In a computing-machine, the combination of a wheel having a guideway for balls in 80 its periphery; balls for said guideway; a setting mechanism carried by said wheel and consisting of a frame having a series of movable parts for determining the extent of movement of said wheel; a series of key-operated devices each, when operated, adapted to make contact with a particular movable part of said setting mechanism; means for moving the series of key-operated devices to make contact 85 between an operated device and its said movable part for actuating the latter; a printing mechanism set by said wheel; an operating mechanism comprising a swinging bar for actuating said wheel by striking said actuated 90 movable part and moving the wheel thereby; and connections therewith for making the printing impression.

29. In a computing-machine, the combination of a wheel having a guideway for balls in 95 its periphery; a setting mechanism carried by said wheel and consisting of a frame having a 100 series of movable parts for determining the extent of movement of said wheel; a series of key-operated devices each, when operated, adapted to make contact with a particular movable part of said setting mechanism; means for moving the series of key-operated devices to make contact 105 between an operated device and its said movable part for actuating the latter; a printing mechanism set by said wheel; an operating mechanism, comprising a swinging bar for actuating said wheel by striking said actuated 110 movable part and moving the wheel thereby; means for moving the balls with the wheels; means operated from said operating mechanism, for holding said balls, while said wheel is returned to initial position; and connections with the operating mechanism for making the printing impression.

30. In a computing-machine, the combination of a wheel having a guideway for balls in 115 its periphery; a setting mechanism carried by said wheel and consisting of a frame having a 120 series of movable parts for determining the extent of movement of said wheel; a series of key-operated devices, each having a setting movement and an operating movement and each, when operated, adapted to make contact 125 with the operating mechanism for making the printing impression.

tact with a particular movable part of said setting mechanism; means for moving the series of key-operated devices to make contact between an operated device and its said movable part for actuating the latter; a printing mechanism set by said wheel; an operating mechanism comprising a swinging bar for actuating said wheel by striking said actuated movable part and moving the wheel thereby; and connections therewith for making the printing impression.

30. In a computing-machine, the combination of a wheel having a guideway for balls in its periphery; balls for said guideway; a setting mechanism carried by said wheel and consisting of a frame having a series of movable parts for determining the extent of movement of said wheel; a series of key-operated devices, each having a setting movement and an operating movement and each, when operated, adapted to make contact with a particular movable part of said setting mechanism; means for moving the series of key-operated devices to make contact between an operated device and its said movable part for actuating the latter; a printing mechanism set by said wheel; an operating mechanism, comprising a swinging bar for actuating said wheel by striking said actuated movable part and moving the wheel thereby; means for moving the balls with the wheel; means operated from said operating mechanism, for holding said balls while said wheel is returned to initial position; and connections with the operating mechanism for making the printing impression.

31. In a computing-machine, the combination of an oscillating ball-wheel having a guideway or channel for balls; means for moving the balls with the wheel in one direction; means for preventing movement of the balls with the wheel in the other direction; setting mechanism for determining the degree of oscillation of said wheel; a printing mechanism set by said wheel; an operating mechanism for moving said wheel correspondingly to said setting mechanism and for returning said wheel to initial position; and connections with the operating mechanism for making the printing impression.

32. In a computing-machine, the combination of a wheel having a guideway for balls in its periphery; balls for said guideway; a setting mechanism carried by said wheel and consisting of a frame having a series of movable parts for determining the extent of movement of said wheel; a series of key-operated devices, each, when operated, adapted to make contact with a particular movable part of said setting mechanism; means for moving the series of key-operated devices to make contact between an operating device and its said movable part for actuating the latter; a printing mechanism set by said wheel; an operating mechanism comprising a swinging bar for ac-

tuating said wheel by striking said actuated movable part and moving the wheel thereby; means for moving the balls with the wheel; means operated from said operating mechanism, for holding said balls, while said wheel is returned to initial position; an indicator-arm, for indicating the heights of the registering column of balls, normally held in non-indicating position; means for releasing said arm at will to make contact with the top of said column; and connections with the operating mechanism for making the printing impression.

33. The combination, in a computing-machine, of a registering mechanism; a setting mechanism for said registering mechanism consisting of a movable frame having a series of pins adapted to be projected into a plane; springs for returning said pins to initial position; a universal dog for sustaining any operated pin in its projected position; a series of key-operated devices, each, when operated, adapted to move into position for moving the series of key-operated devices to make contact between an operated device and its particular pins for projecting the latter; a bar having a uniform arc of movement adapted to strike an operated pin, and to move said setting mechanism and said registering device proportionately to the value of the operated key; an operating mechanism for operating said bar and for returning the same and said registering mechanism to initial position; means for releasing said universal dog; and operating connections between the same and said operating mechanism.

34. The combination, in a computing-machine, of a registering mechanism; a setting mechanism for said registering mechanism consisting of a movable frame having a series of pins adapted to be projected into a plane; springs for returning said pins to initial position; a universal dog for sustaining any operated pin in its projected position; a series of key-operated devices, each, when operated, adapted to move into position for moving the series of key-operated devices to make contact between an operated device and its particular pins for projecting the latter; a bar having a uniform arc of movement adapted to strike an operated pin, and to move said setting mechanism and said registering device proportionately to the value of the operated key; a printing mechanism set by said registering mechanism; an operating mechanism for operating said bar and for returning the same and said registering mechanism to initial position and connections therewith for making the printing impression; means for releasing said universal dog; and operating connections between the same and said operating mechanism.

35. The combination, in a computing-machine, of two registering-wheels of different denominations; a bar common to said wheels

adapted to swing to and fro in a definite arc for operating said wheels; a setting mechanism upon each wheel having a series of movable parts adapted to be projected into the path of said bar; a key mechanism for operating said movable parts according to the values of the respective keys by projecting a movable part into the path of said bar; a carrying mechanism operated at intervals by the wheel of lower denomination and consisting of a block upon the wheel of higher denomination adapted to be projected in front of the bar and to be interposed between the same and the setting mechanism of a wheel of higher denomination, said block being of such dimensions as to cause said wheel of higher denomination to be moved one unit-space of the higher denomination in addition to its extent of movement when the block is not interposed in front of said bar; and an operating mechanism.

36. The combination, in a computing-machine, of two registering-wheels of different denominations; a bar common to said wheels, adapted to swing to and fro in a definite arc for operating said wheels; a setting mechanism upon each wheel, having a series of movable parts adapted to be projected into the path of said bar; a key mechanism for operating said movable parts according to the values of the respective keys by projecting a movable part into the path of said bar; a carrying mechanism operated at intervals by the wheel of lower denomination and consisting of a block upon the wheel of higher denomination adapted to be projected in front of the bar and to be interposed between the same and the setting mechanism of the wheel of higher denomination, said block being of such dimensions as to cause said wheel of higher denomination to be moved one unit-space of the higher denomination in addition to its extent of movement when the block is not interposed in front of said bar; an operating mechanism; and a locking mechanism for said wheels, operated by said motor mechanism for engaging said wheels and disengaging therefrom during periods of their movement by said bar; and

37. The combination in a computing-machine, of two registering devices of different denominations; a bar common to said registering devices adapted to move to and fro within definite limits for operating said devices; a setting mechanism for each registering device having a series of movable parts adapted to be projected into the path of said bar; a key mechanism for operating said movable parts according to the values of the respective keys by projecting a movable part into the path of said bar; a carrying mechanism operated at intervals by the registering device of lower denomination and comprising a series of blocks upon said bar, one for each

projected in front of the bar and to be interposed between the same and the setting mechanism of a registering device of higher denomination, said block being of such dimensions as to cause said registering device of higher denomination to be moved one unit-space of the higher denomination in addition to the extent of its movement when the block is not interposed in front of said bar; and an operating mechanism.

38. The combination, in a computing-machine, of two registering devices of different denominations; a bar common to said registering devices adapted to move to and fro within definite limits for operating said devices; a setting mechanism for each registering device having a series of movable parts adapted to be projected into the path of said bar; a key mechanism for operating said movable parts according to the values of the respective keys, by projecting a movable part into the path of said bar; a carrying mechanism operated at intervals by the registering device of lower denomination and comprising a series of blocks upon said bar, one for each registering device, and adapted to be projected in front of the bar and to be interposed between the same and the setting mechanism of the registering device of higher denomination, said block being of such dimensions as to cause said registering device of higher denomination to be moved one unit-space of the higher denomination in addition to the extent of its movement when the block is not interposed in front of said bar; and a locking mechanism for said wheels, operated by said motor mechanism for engaging said wheels and disengaging therefrom during periods of their movement by said bar; and an operating mechanism.

39. In a computing-machine, the combination of a ball-wheel B' having a guideway or channel B for balls in the periphery thereof; balls for said guideway; a bar C adapted to swing to and fro in a definite arc; a setting-frame b upon said wheel, having a series of radial pins b¹⁰ adapted to be projected into the path of said bar C; a key mechanism for operating said pins according to the values of the keys; a dog b' upon said wheel for moving the balls with the wheel; an operating mechanism, and a dog b⁴, operated by said motor mechanism for engaging said balls when the wheel is moved to its initial position.

40. In a computing-machine, the combination of a ball-wheel B' having a guideway or channel B for balls in the periphery thereof; balls for said guideway; a bar C adapted to swing to and fro in a definite arc; a setting-frame b upon said wheel having a series of radial pins b¹⁰ adapted to be projected into the path of said bar C; a key mechanism for operating said pins according to the values of the keys; a dog b' upon said wheel for moving the balls with the wheel; a dog b⁴ oper-

ated by said motor mechanism for engaging said balls when the wheel is moved to its initial position; means for locking said bar C to the setting-frame during the positive stroke 5 of the latter; and means for disconnecting said bar from the setting-frame during its negative stroke.

41. In a computing-machine, the combination of two ball-wheels B' each having a guideway or channel B for balls in the periphery thereof; balls for said guideway; a bar C adapted to swing to and fro in a definite arc; a setting-frame b upon said wheel having a series of radial pins b¹⁰ adapted to be projected into the path of said bar C; a key mechanism for each wheel for operating said pins according to the values of the keys; a dog b' upon said wheel for moving the balls with the wheel; an operating mechanism; a dog b⁴, operated by 10 said mechanism for engaging said balls when the wheel is moved to its initial position, indicator-arms for indicating the height of the registering columns of balls normally held in non-indicating position; and means for releasing 15 said arms at will to make contact with the tops of said columns.

42. In a computing-machine, the combination of a ball-wheel B' having a guideway or channel B for balls in the periphery thereof; 20 balls for said guideway; a bar C adapted to swing to and fro in a definite arc; a setting-frame b upon said wheel having a series of radial pins b¹⁰ adapted to be projected into the path of said bar C; a key mechanism for operating 25 said pins according to the values of the keys; a dog b' upon said wheel for moving the balls with the wheel; an operating mechanism; a dog b⁴ operated by said mechanism for engaging said balls when the 30 wheel is moved to its initial position; means for locking said bar C to the setting-frame during the positive stroke of the latter; and means for disconnecting said bar from the setting-frame during its negative stroke, indicator-arms for indicating the height of the 35 registering columns of balls normally held in non-indicating position; and means for releasing said arms at will to make contact with the tops of said columns.

43. The combination of a registering mechanism; the keys A²; the bell-crank levers A¹⁰ connected to said keys; the springs a for said bell-crank levers; the notched and longitudinally-movable setting-bars A connected to said 40 bell-crank levers; the oscillating frame A³ for the bars A; the latch A' common to the bars and adapted to engage the notches thereof; a setting mechanism having a series of parts corresponding with the bars A, and adapted to be 45 operated thereby for determining the extent of movement of the registering mechanism; and an operating device for operating the frame A³ and for releasing the latch A'.

44. In a computing-machine, the combina-

tion of the ball-wheel B' having a guideway or 65 channel B for balls in the periphery thereof; balls for said guideway; a bar C adapted to swing to and fro in a definite arc; a setting-frame b upon said wheel having a series of radial pins b¹⁰ adapted to be projected into the 70 path of said bar C; a series of keys A²; a series of notched and longitudinally-movable setting-bars A; an oscillating frame A³ adapted to move said bars to and from said pins; connections between each key A² and a setting-bar A; a spring for moving each setting-bar in one direction; a latch A² for engaging the notches in the series of setting-bars; an operating mechanism for oscillating the frame A³ 75 and said bar C, and for operating said ball-wheel; a dog b' upon said ball-wheel for moving the balls with the wheel when the latter is moved by the bar C; and a dog b⁴ operated by said mechanism for engaging said balls when the wheel is moved to its initial position. 80

45. A recording-printing mechanism consisting of type-segments normally set to print zero; means for setting said type-segments; a platen-frame movable to and from said type-segments; a movable platen carried by said 90 frame, and means operated by said wheels for moving said platen across said type-segments; means for stopping the platen in printing position opposite the highest operated type-segment and the type-segments of lower denominations; and an operating mechanism. 95

46. In a computing-machine, the combination of a key mechanism; a registering mechanism comprising oscillating wheels; a printing mechanism consisting of a series of type-segments connected respectively to said wheels and normally set to print zeros; a platen-frame movable to and from said type-segments; a movable platen carried by said frame; means operated by said wheels for moving said platen 100 across said type-segments; means for stopping the platen in printing position opposite the highest operated type-segment and the type-segments of lower denominations; and an operating mechanism for operating said registering mechanism and said platen-frame. 110

47. In a computing-machine, the combination of a key mechanism; a registering mechanism comprising oscillating wheels; a printing mechanism consisting of a series of type-segments connected respectively to said wheels and normally set to print zeros; a platen-frame movable to and from said type-segments, a movable platen carried by said frame; means operated by said wheels for moving said platen across said type-segments; means for stopping the platen in printing position opposite the highest operated type-segment and the type-segments of lower denominations; a carrying mechanism for operating the registering mechanism; means for preventing the carrying operations of said registering mechanism from operating said type- 115 120 125

segments; and an operating mechanism for operating said registering mechanism and said platen-frame.

48. In a printing mechanism for computing-machines, the combination of an oscillating registering mechanism; an arm operated thereby and proportionately to the movements thereof; a type-segment normally set to print zero; a link connecting said arm and said type-segment; a platen-frame and means for producing a printing impression thereof against the type - segment; a transversely-movable platen carried by said platen-frame; a normally latched bar for moving said platen; a stop for said bar released by the movement of said arm; means for unlatching said bar; and a spring for operating said bar to rest against said stop.

49. The combination, in a computing-machine of a series of oscillating wheels each representing a denomination and each a key mechanism, having a guideway or channel for balls in the periphery thereof; balls for said guideway; means for actuating said wheels to move the balls therein in correspondence with said key mechanism; a carrying-bar supported upon each wheel, and having a supporting-pin at one end normally resting in said channel for supporting a column of balls thereon; a movable support upon said wheel for said bar; a fulcrum upon said bar consisting of a pin adapted to engage a ball in said column when said column indicates the maximum of its denomination; a carrying-frame common to said wheels and actuated at each operation of the machine, and a connection therefrom to the other end of said bar; a sliding plate upon each ball-wheel and connections therefrom to the carrying-bar on the wheel of next higher denomination; whereby, when a ball in said column rests under the fulcrum-pin, said ball is pinched and held, and the balls below said pin, and resting upon the supporting-pin are released; an operating mechanism for said carrying-frame and for said wheels; and means operated by said sliding plate for causing the wheel of next higher denomination to be actuated one additional ball-space to discharge a single ball in its guideway.

50. The combination in a computing-machine, of an operating mechanism having a regular excursion at each operation of the machine, two registering elements, means for determining the degree of movement imparted to the registering elements by the operating mechanism, transfer devices operated by one of the registering elements to interpose a movable part in the regular connection between the operating mechanism and the remaining registering element whereby the latter will be moved by the operating mechanism one degree farther than it would have been had the movable part not been interposed.

51. The combination in a computing-ma-

chine, of an operating mechanism having a regular excursion at each operation of the machine, two registering elements, means for controlling the degree of movement imparted to the registering elements from the operating devices, means interposed between the operating mechanism and the registering elements, and a movable part arranged to be moved by one registering element so as to be interposed in the connection between the remaining registering element and the operating mechanism whereby said second element will be moved by its operating device an additional unit.

52. The combination in a computing-machine, of two registering elements, an operating mechanism, an oscillating bar for operating the registering elements, means for controlling the movements of said elements by said bar, and a movable device arranged to be moved by one of said elements so as to be interposed between said bar and the companion element to give the latter a movement in addition to its regular registering movement.

53. The combination with a series of type-carriers and means for setting the same, of a platen movable laterally in respect to the carriers, and means for automatically adjusting the platen according to the carriers set.

54. A printing mechanism consisting of type-carriers arranged to normally print a certain character, means for setting said type-carriers to print other characters, a movable platen, and means for adjusting the platen, to print only from the carrier that has been moved from normal position and the carriers to one side only of the same.

55. The combination with two registering elements, transfer devices between said elements, type-carriers, means connecting said carriers to the respective registering elements so that they will be correspondingly moved, and means for shifting this connection when a transfer is made whereby the type-carrier will be moved one unit less than its registering element which is receiving the transfer.

56. The combination with an operating mechanism, of two registering elements, means for connecting the registering elements to the operating mechanism at different points, and a transfer mechanism, including a movable part, which is interposed in the connection between the operating mechanism and registering element to cause the connection to be sooner affected and thus cause a greater degree of movement.

57. The combination with an operating-bar having a regular excursion at each operation of the machine, of two registering elements, movable devices mounted on said elements and arranged to be adjusted to be actuated by said bar during the regular movement of the machine, and transfer devices, including a movable part, carried by said bar and arranged to be interposed between said bar and

said movable devices on the counting elements to move them an additional degree.

58. The combination with an operating mechanism, of registering elements adapted to be moved thereby, type-carriers, means for operating the type-carriers directly from the registering elements, and means interposed between the type-carriers and registering elements for operating said carriers from the registering elements at all times except when said registering elements receive an additional transfer movement.

59. The combination with type-carriers, of registering elements, transfer devices between said elements, and means interposed between the registering elements and type-carriers whereby the latter are set according to the regular movements of the registering elements, but not by their transfer movements.

60. The combination with type-carriers, of a series of registering elements, a series of keys, means for operating the registering elements according to the value of the keys operated, transfer devices between the registering elements, and means for setting the type-carriers according to the primary movement of said registering elements, thus preventing the transfer movements of said elements affecting the type-carriers.

61. The combination in a computing-machine, of a registering device, a setting mechanism movable with said registering device and consisting of a movable frame having a series of movable parts for determining the extent of movement of said registering device, means for operating the movable parts, and an operating mechanism having a regular excursion at each operation of the machine and adapted to contact with the movable parts of the setting device which has been adjusted to operative position.

62. The combination in a computing-machine, of a registering-wheel carrying a series of movable projections, an operating member having a regular excursion at each operation of the machine, and means for setting the desired movable projection of the registering-wheel so that it will be engaged by the said operating member in its excursions.

63. The combination in a computing-machine of a registering-wheel carrying a series of spring-pressed plungers, an operating member having a regular excursion at each operation of the machine, and means for setting the desired plunger whereby the wheel is moved to a greater or less extent by the operating member.

64. The combination in a computing-machine, of a registering-wheel carrying a series of movable projections, an operating member having a regular excursion at each operation of the machine, means for setting the desired projection in the path of the movable member, and devices for coupling the movable

member to the registering-wheel to prevent independent movement of the latter.

65. The combination in a computing-machine, of a registering-wheel carrying a series of spring-pressed plungers, an operating-bar having a regular excursion at each operation of the machine, means for moving any desired plunger into the path of said bar, a device carried by said bar for coupling the same to the registering-wheel to prevent independent movement of the latter, and means for tripping said coupling device at each end of the stroke of the bar.

66. In a computing-machine, the combination with an operating mechanism, of a registering-wheel arranged to be moved a greater or less distance according to the value to be registered, a series of balls carried by said wheel, means for causing the balls to move with the wheel in one direction, and independent automatic means for holding the balls stationary when the wheel moves in the opposite direction.

67. In a computing-machine, the combination of an oscillating ball-wheel having a guideway or channel for the reception of balls, balls in said channel, means for moving the balls with the wheel in one direction, independent automatic means for preventing the movement of the balls with the wheel in the other direction, and means for moving the wheel to a greater or less extent according to the value to be registered.

68. In a computing-machine, the combination with two oscillating ball-wheels representing different denominations, each having a guideway or channel for balls, balls in said channel, means for moving the balls with the wheels in one direction, independent automatic means for preventing the movement of the balls with the wheels in the other direction, and transfer mechanisms between the respective wheels for causing an additional forward transfer movement of one of the wheels equal to one unit.

69. In a computing-machine, the combination with a plurality of units arranged in series, the heights of the several series denoting the values registered, of type-carriers, and means connected to the type-carriers arranged to operate above the series of movable units and be arrested in their movements by contacting with the columns of units to set the type-carriers to print the total represented by the heights of the respective series or columns.

70. In a computing-machine, the combination with a series of registering-wheels having ball-channels, balls mounted in said channels and arranged to be moved by said wheels, printing devices, means for setting the printing devices controlled by the position of the balls in the respective channels, and devices operated at will and arranged to hold the setting devices in check.

71. In a computing-machine, the combination of a series of wheels having ball-channels, balls in said channels, means for supporting the balls independently of the channels, means 5 for collecting the balls upon said supports governed by the movements of the wheels, a series of type-carriers, means connected to the type-carriers and coating with the balls collected upon the aforesaid supports, where-
10 by said carriers are positioned according to the heights of the columns formed by said balls, and devices operated at will and arranged to hold the setting devices in check.
72. In a computer, the combination with a 15 registering mechanism comprising a series of units arranged to be accumulated upon a suitable support, a movable member for accumulating said units, a type-carrier, means for setting the type-carrier according to the move-
20 ments of the movable member, said means being adjustable at will to also set the type-carrier to print the sum of several transactions according to the sum value of the accumulated units.
- 25 73. In a computing-machine, the combination with an operating mechanism, of a series of keys, movable spring-pressed setting-plungers operated from said keys, latches for said plungers arranged to be tripped upon each 30 operation of the machine to allow the plungers to return to normal position, and auxiliary means for preventing the return of the plungers at the regular operation of the machine.
- 35 74. In a computing-machine, the combination with an operating mechanism, of a series of automatic setting devices for controlling the movements of the same, a series of keys, connections between the keys and setting de-
40 vices arranged to be operated independently of the keys upon each operation of the machine to actuate said setting devices, latches for holding the setting devices in position ar-
45 ranged to be operated upon each operation of the machine, and a second latching means for preventing the operation of said latches upon the operation of the machine.
- 50 75. In a computing-machine, the combina-
55 tion with a series of type-carriers, of a move-
able platen controlled by the type-carriers, with provisions for automatically adjusting the platen upon the operation of the machine into such position as to print from the operated type-carrier and such of the other type-
carriers as are situated at one side only of said operated carrier.
- 60 76. In a computing-machine, the combina-
65 tion with a series of type-carriers, of a move-
able platen automatically positioned to print from only a certain predetermined number of said type-carriers without printing from the remaining carriers, according to the combi-
nation of type-carriers operated.
77. In a computing-machine, the combina-
tion with a series of setting elements, of a 65 single latch-plate therefor; a releasing device for said latch-plate; an operating mechanism; means for actuating said releasing device by the operating mechanism at each operation of the machine; and manually-operative means 70 for shifting said releasing device out of co-operative alinement with said latch-plate.
78. In a computing-machine, the combina-
tion with a series of registering elements, of a series of setting-stops for determining the 75 extent of movement of said registering elements; a series of stop-actuating devices cor-
responding to said stops but all normally out of co-operative alinement therewith; a series of keys; means controlled by said keys for 80 moving their respective stop-actuating devices into alinement with the corresponding stop; and means for subsequently moving said actuating devices independently of said keys to set the said stops.
- 85 79. In a computing-machine, the combina-
tion with a series of reciprocating registering elements having graduated movements, of counting devices moved in one direction by said registering elements; an operating mech-
anism for said registering elements; and transfer devices controlled by said counting de-
vices when a predetermined number of units have been added on the same, to cause the operating mechanism to give the registering 90 element of the next higher denomination a positive transfer movement in excess of its normal movement of registration, said transfer movement occurring as a cumulative accompaniment to said normal movement of 95 registration.
80. In a computing-machine, the combina-
tion with a series of reciprocating registering elements having graduated movements, of counting devices moved in one direction by 105 said registering elements, an operating mech-
anism for said registering elements including an operating member having regular excursions at each operation of the machine, said member directly engaging said registering 110 elements to impart the normal registering movements thereto; and transfer devices set by said counting devices when a predeter-
mined number of units have been added on the same, to cause the operating member to 115 give the registering element of the next higher denomination a positive transfer movement in excess of its normal movement of registration.
81. In a computing-machine, the combina-
tion with an operating mechanism having 120 regular excursions at each operation of the machine, of a series of reciprocating register-
ing elements having graduated movements; means for determining the degree of move-
ment imparted to said registering elements 125 by the operating mechanism; and transfer devices operated by one of the registering

elements to cause the operating mechanism to give the registering element of the next higher denomination a positive transfer movement in excess of its normal movement of 5 registration, said transfer movement occurring during the same extent of the excursion of said operating mechanism as that in which

the normal movement of registration takes place.
